HEAT EXCHANGE PANELS

Filed July 17, 1962

2 Sheets-Sheet 2

transversely of the panel between the inflow and return flow ducts.

3. A heat exchange device according to claim 1, wherein in both the non-circulating ducts and the circulating ducts have a zig-zag formation and include spaced portions extending longitudinally of the panel and spaced portions extending transversely of the panel.

4. A heat exchange device comprising a substantially rectangular panel of flexible material, the panel consisting of a sheet having a front side and a rear side, a plurality of substantially semi-circular ducts on said front side of the sheet, at least the greater portion of the length of the majority of said plurality of ducts extending transversely of said sheet and occupying the greater portion of the area of the sheet, the totality of said ducts having the same cross-sectional area and being spaced edge-to-edge on the sheet, alternate ones of said totality of ducts having their ends closed to provide non-circulating ducts and being filled with a fluid to withstand external pressure, the ducts between said alternate ones having their ends open to provide circulating ducts, and additional semi-circular inlet and outlet ducts having said same cross-sectional area on said front side of said sheet, said additional ducts being positioned longitudinally with respect to the sheet and being connected with said circulating ducts for passing a thermal fluid through said circulating ducts.

5. A heat exchange device according to claim 4, said additional ducts consisting of two ducts extending along

opposite longitudinal edges of said sheet, the ends of said circulating ducts being connected to said additional ducts at longitudinally spaced intervals equal to the width of the ducts, both of said two ducts having the ends thereof at one end of said sheet closed and having the ends thereof at the other end of the sheet open, one of said open ends of said two ducts providing an inlet for the thermal fluid, the other of said open ends of said two ducts providing an outlet for the thermal fluid.

6. A heat exchange device according to claim 4, the lesser portion of said plurality of said ducts extending longitudinally with respect to said sheet.
